L. H. MORIN

WINDOW OPERATING DEVICE

Filed Oct. 22, 1921

FIG. 1.

FIG. 3.

FIG. 2.

FIG. 4.

INVENTOR

Louis H. Morin,

BY

Edgar Date, Jr.

ATTORNEY

UNITED STATES PATENT OFFICE.

LOUIS H. MORIN, OF NEW YORK, N. Y., ASSIGNOR TO SOSS MANUFACTURING CO., OF BROOKLYN, NEW YORK, A CORPORATION OF MAINE.

WINDOW-OPERATING DEVICE.

Application filed October 22, 1921. Serial No. 509,663.

To all whom it may concern:

Be it known that I, LOUIS H. MORIN, a citizen of the United States, and residing at New York, in the county of Bronx and 5 State of New York, have invented certain new and useful Improvements in Window-Operating Devices, of which the following is a specification, such as will enable those skilled in the art to which it appertains to 10 make and use the same.

This invention relates to devices for operating windows, window panels and the like and particularly to the windows or window panels of motor vehicles, and the object of 15 the invention is to provide a window operating device of the class specified which is mounted in connection with the framework of the window or the body of a motor vehicle and in operative connection with a 20 window or window panel, whereby the operation of said device will raise and lower said window or window panel depending upon the direction in which the operating device is rotated; and with this and other 25 objects in view the invention consists in a device of the class specified which is simple in construction and operation and efficient in use, and which is constructed as herein-after described and claimed.

30 The invention is fully disclosed in the following specification, of which the accompanying drawing forms a part, in which the separate parts of my improvement are designated by suitable reference characters 35 in each of the views, and in which:—

Fig. 1 is a diagrammatic inside view of a part of a motor vehicle door showing my improved window panel operating device mounted in connection therewith and indicating the method of its use;

Fig. 2 a partial section on the line 2—2 of Fig. 1 and on an enlarged scale;

Fig. 3 a partial section on the line 3—3 of Fig. 1 but showing only the window panel 45 and the operating device therefor; and

Fig. 4 an enlarged detail view of a modified form of a rotatable element or shaft which I may employ.

In Fig. 1 of the drawing I have shown for 50 the purpose of illustrating one use of my invention, a part of a motor vehicle door 10 which is diagrammatically illustrated in said figure, the bottom portion of said door being hollow as shown at 11, and the approximate central portion thereof being pro-

vided with a transverse member 12 which joins the side rails or frame-work members 13 of the door, and mounted in the door 10 is a window panel 14 which is adapted to be moved vertically in the side frame members or rails 13 of the door 10 by my improved operating device 15.

The operating device 15 comprises a rotatable shaft or element 16 which is mounted centrally and vertically of the door 10 and 60 in the compartment 11 thereof, and extends upwardly into the transverse member 12 of the door, and the upper end of which has a bearing in a bracket 17, the lower end of said shaft being mounted in a suitable 65 bearing 18.

The shaft 16 in the construction shown in 70 Figs. 1 to 3 inclusive is threaded throughout its entire length and the threads are of the same pitch throughout, while in Fig. 4 of 75 the drawing I have shown the upper end portion of the shaft 16 provided with a plurality of threads 19 of one pitch, while the remainder of said shaft is provided with threads 20 of a different pitch.

The bracket 17 is approximately box-shaped in form and is provided with laterally directed ears 21 through which are passed screws 22 to secure the bracket to the member 12 of the door, and mounted 80 transversely of said bracket at one side of the shaft or rotatable element 16 is a stub shaft 23 which projects through the inner face of said bracket and is provided with a crank lever 24 by means of which the shaft 90 23 may be rotated, and secured to said shaft within the bracket 17 is a rotatable threaded member or gear 25, the pitch of the threads of which are such as to engage the threads of the shaft 16 whereby the rotation of the gear 25 by the crank lever 24 will cause the shaft 16 to be rotated.

Mounted upon the shaft or rotatable element 16 is a nut or block 26 which is threaded to correspond with the threads of 100 the shaft 16, and said nut or block is provided with oppositely directed and projecting pins 27 in connection with which backwardly directed fork-shaped extensions 28 on a U-shaped strip 29 are adapted to cooperate, said strip 29 being secured to the lower edge portion of the window panel 14 as clearly shown in Fig. 3 of the drawing. With this construction it will be seen that 105 the rotation of the shaft 16 by means of the 110

2
gear 25 and lever 24 will cause the nut or block 26 to be raised or lowered by the shaft 16, which operation will correspondingly raise and lower the window panel 14, and 5 by reason of the fork-shaped members 28 engaging the pins 27 on the block 26 a slight lateral movement of the window panel 14 is permitted, and this will prevent the jamming or binding of said window panel 10 in the operation thereof.

With the construction of the shaft 16, as shown in Fig. 4 of the drawing, it will be apparent that the gear 25 will mesh with the threads 19 and the pitch of the threads 15 of the gear 25 will be such as to operate in connection with the pitch of the threads 19, while the block 26 will be threaded to correspond with the pitch of the threads 20 of said shaft. It will be apparent that with 20 this construction I may regulate the rotation of the shaft 16 as well as the movement imparted to the window panel 14.

It will be understood that while I have shown a specific use of my improvement that 25 I am not necessarily limited to this use, nor am I limited to the specific method of supporting the various operative parts of my improved device, and changes in and modifications of the construction herein shown 30 and described may be made, within the scope of the appended claims, without departing from the spirit of my invention or sacrificing its advantages.

Having fully described my invention, 35 what I claim as new and desire to secure by Letters Patent, is:—

1. A window operating device of the class described comprising a rotatable screw shaft the threads of which extend from one end 40 portion of said shaft to the other, means for supporting said shaft, a gear mounted transversely of one end portion of said shaft, the teeth of said gear meshing directly with the teeth of said shaft, means for rotating

said gear to impart rotary movement to 45 said screw shaft, and means engaging the threads of said screw shaft and mounted in connection with the window to be operated whereby the rotation of said shaft will move said last named means longitudinally there- 50 of.

2. A window operating device of the class described comprising a vertically arranged screw shaft, means for supporting the end portions of said shaft, said screw shaft being threaded throughout its entire length, and the supporting means at one end of said shaft comprising a box-shaped housing, a worm rotatably mounted in said housing and extending transversely of said shaft and meshing with the threads thereof, and means in threaded engagement with said shaft and mounted in connection with the window to be operated whereby the rotation of said shaft by said worm will actuate said last 65 named means longitudinally of the shaft and correspondingly move said window.

3. A window operating device of the class described comprising a vertically arranged screw shaft, means for supporting the end portions of said shaft, said screw shaft being threaded throughout its entire length, and the supporting means at one end of said shaft comprising a box-shaped housing, a worm rotatably mounted in said housing and extending transversely of said shaft and meshing with the threads thereof, means in threaded engagement with said shaft and mounted in connection with the window to be operated whereby the rotation of said shaft by said worm will actuate said last 75 named means longitudinally of the shaft and correspondingly move said window.

In testimony that I claim the foregoing 85 as my invention I have signed my name this 20th day of October, 1921.

LOUIS H. MORIN.
